ELECTRIC IRON

Filed Feb. 1, 1924

UNITED STATES PATENT OFFICE

CARROLL DE ATLEY, OF BALTIMORE, MARYLAND, ASSIGNOR TO SUPERIOR STEAM IRON COMPANY, INC., OF BALTIMORE, MARYLAND, A CORPORATION OF MARYLAND

ELECTRIC IRON

Application filed February 1, 1924. Serial No. 689,868.

The invention relates to new and useful improvements in pressing irons, and more particularly to a pressing iron equipped with means for supplying moisture at the ironing face of the iron.

An object of the invention is to provide an iron of the above character which is provided with a body portion having a superheating steam chamber therein and ports connected with said chamber and leading to the ironing face of the iron, which body portion is so constructed that access may be readily had to the superheating chamber and the ports for cleaning the same.

15 A further object of the invention is to provide a pressing iron of the above type wherein said body portion is divided horizontally so as to give ready access to the superheating chamber and to the ports 20 which convey the moisture to the ironing face of the iron.

A still further object of the invention is to provide an iron of the above type with an electric heating element, which is placed 25 on top of the body portion and which is held pressed against said body portion by means of a plate and a clamping head, which clamping head serves as a means for conducting the steam to the superheating chamber.

30 These and other objects will in part be obvious and will in part be hereinafter more fully disclosed.

In the drawings which show by way of 35 illustration one embodiment of the invention—

Figure 1 is a side view of a pressing iron embodying my improvements;

Fig. 2 is an enlarged vertical sectional 40 view of a portion of the iron, said section being taken longitudinally of the iron;

Fig. 3 is a composite view showing an under plan view of the upper section and upper plan view of the lower section;

45 Fig. 4 is a sectional view through the block which secures the heating element to the body portion of the iron and which also serves as a means for conveying the steam to the superheating chamber, and

50 Fig. 5 is a sectional view through the body

portion of the iron on the line 5—5 of Fig. 3.

My improved iron consists of a body portion which is provided with a superheating steam chamber located centrally of the body portion and extending lengthwise thereof. Said body portion is formed in two sections, one disposed above the other and the contacting faces of said sections lie in a plane which passes through a superheating chamber preferably midway the depth thereof. The lower section of the iron is provided with a channel which extends about the superheating chamber and is provided with ports which lead through the lower portion and open at the ironing face of the iron. The upper section is provided with channels which connect the superheating chamber with the channel containing the ports. On top of the body portion of the iron there is an electrical heating element which is relatively flat and is shaped so as to conform in a general way to the outline of the body portion of the iron. Directly on top of the heating element is a flat plate 14. Said flat plate is secured against the heating element and the heating element in turn clamped against the body portion by means of a nut threaded on to a post passing up through the heating element, and by means of a block having a threaded pipe section which screws into the body portion so that the block bears against the flat plate. This block serves as a means for introducing the steam to the heating chamber. The heating element and parts on the upper face of the body portion are all covered by a shell having a handle, which parts are of the usual construction.

Referring more in detail to the drawings, 90 my improved iron includes a body portion having an upper section 1 and a lower section 2. These sections make contact with each other along a plane parallel with the ironing face 3 of the iron, and midway between the upper and lower faces of the body portion. The lower section 2 of the iron is formed with a central depression or recess 4 which is of substantially uniform depth throughout and shaped so as to conform gen- 95 100

erally to the configuration of the body portion. The upper section 1 is formed with a recess 5 in its under face, which together with the central depression or recess 4 forms a superheating chamber for the steam. It will be noted that the plane between the two sections is midway between the upper and lower faces of this superheating chamber. The upper face of the lower section 2 is also provided with a channel 6 which is substantially parallel with the side edges of the pressing iron and also the rear end of the iron. Said channel extends all the way around the superheating chamber. Said body portion 2 is also formed with a series of spaced ports 7 which open into the channel 6 at their upper ends, and which open at the ironing face of the body portion of the iron at their lower ends. At the extreme forward tip end of the iron there is also a chamber 8 leading into the channel 6 and a series of ports 9 are provided at the extreme forward end of the iron, which open into this chamber 8. The lower face of the upper section 1 of the iron is provided with two short channels 10 and 11. These channels are for the purpose of connecting the superheating chamber formed by the portions 4 and 5 with the channel 6, as clearly shown in Figure 5 of the drawings. The steam in the superheating chamber passes through these channels 10 and 11 into the channel 6 and thence out through the ports 9 to the ironing face of the iron.

35 The two sections 1 and 2 are clamped firmly together by means of clamping bolts 12, 12. There are five clamping bolts shown in the drawings, but the number may be changed to suit conditions. These bolts are all countersunk so that the upper face of the section 1 is smooth and flat. Mounted directly on the upper face of the body portion is an electrical heating element 13 of the usual well-known construction. On top of the heating element is a plate 14 which serves to press the heating element against the upper face of the body portion of the iron. A post 15 is secured to the upper section of the body portion and projects up through the heating element and clamping plate 14. A nut 16 is threaded on to this post and presses a collar 17 against the plate 14, and thus clamps the plate and heating element on the body portion of the iron.

50 A block 18, preferably rectangular in shape is provided with a short section of threaded pipe 19. This threaded section of pipe 19 is adapted to pass down through an opening in the clamping plate 14, and also an opening in the heating element 13, and is threaded into the upper section 1 of the body portion. The threaded section of the pipe is preferably of such length as to extend substantially through the upper section of this body portion, and the pipe opens into the

superheating chamber between the two sections. This rectangular block 18 has a cylindrical chamber 20 which extends longitudinally through the block and the pipe 19 opens into this chamber. There is an opening directly in line with the pipe 19 leading into this chamber which is closed by a cap screw 21. One end of the chamber 20 is closed by a cap screw 22, while a supply pipe 23 is threaded into the other end of the chambered block. Mounted on the body portion of the iron and enclosing the block 18 and the heating element and the clamping element is a shell 24, which is of the usual construction. A handle 25 is secured to the shell in any well-known way. The post 15 extends up through the shell and a cap nut 26 threaded on to the end of the post serves to clamp the shell on the body portion. It will be noted that the upper part of the body portion is cut away at 27 to form a seat for the shell, so that the shell extends over said body portion for a short distance. Said shell is provided with an opening through which the pipe 23 extends and said pipe is connected to a suitable source of supply so that steam may be furnished to the iron. The electrical contacts or terminal posts 28 from the heating element 13 also extend up through the shell. The handle is provided with a supporting collar 29 for the electrical connection with the contacts or terminals 28.

It will be noted that my improved iron is very simple in construction and may be readily taken apart for cleaning. When the two sections of the body portion are separated, access is had directly to the superheating chamber, and also to the channel for supplying steam to the ports leading to the ironing face of the iron. When the upper section is removed, the heating chamber may be readily scraped so as to remove all rust and the like therefrom. Likewise, the channel 6 may be cleaned in the same way, and a wire or the like may be forced through each port 7 for freeing the same of any rust or dirt accumulating therein. The heating element being clamped directly against the upper face of the body portion of the iron, will serve as a ready means for heating the chamber formed by the recesses 4 and 5 and thus superheating the steam which is led into said chamber. The superheated steam passes over through the channels 10 and 11 to the channel 6 and thence through the ports 7 to the ironing face of the iron.

It is obvious that minor changes in the details of construction may be made without departing from the spirit of the invention as set forth in the appended claims.

Having thus described the invention, what I claim as new and desire to secure by Letters-Patent, is—

1. A pressing iron including in combination a body having a superheating chamber located substantially centrally of the body, means for supplying said chamber with steam, said body having a channel lying in a horizontal plane, surrounding said superheating chamber and connected thereto at a point above the bottom portion of the chamber whereby water of condensation will be trapped in the superheating chamber and regenerated into steam, said body having ports leading from said channel to the pressing face of the iron.

2. A pressing iron including in combination a body having a superheating chamber located substantially centrally of the body, means for supplying said chamber with steam, means for heating said chamber, said body having a channel lying in a horizontal plane, surrounding said superheating chamber and connected thereto at a point above the bottom portion of the chamber whereby water of condensation will be trapped in the superheating chamber and regenerated into steam, said body having ports leading from said channel to the pressing face of the iron, said body being formed of upper and lower separable sections with the contacting faces of said sections lying in a plane so disposed that when the sections are separated access may be had to the channel and chamber for cleaning.

3. A pressing iron including in combination a body having a superheating chamber, located substantially centrally of the body, means supplying said chamber with steam, an electric heating element mounted on the upper face of said body, said means for supplying steam to the chamber including a tube passing through the heating element, said body having a channel formed therein lying in a horizontal plane, surrounding said superheating chamber and spaced therefrom with connecting channels leading to the superheating chamber at points above the bottom thereof whereby water of condensation will be trapped in the superheating chamber and regenerated into steam, said body having ports connecting said channel with the pressing face of said iron.

In testimony whereof, I affix my signature.

CARROLL DE ATLEY.
